UNITED STATES PATENT OFFICE.

ODILON BRISBOIS, OF CHICAGO, ILLINOIS.

ENGINE STARTER.

Application filed July 14, 1923. Serial No. 651,461.

This invention relates to an engine starter of that type involving a driven member which automatically moves into engagement with an engine member for starting the same and that automatically moves out of mesh when the engine overruns the driven member.

It is an object of this invention to provide such a starter which will avoid the detrimental clashing of gears, that will yield upon a tooth-on-tooth engagement, and that functions in a smooth and easy manner.

It is broadly an object of this invention to provide a starter having a sufficiently wide range of yield to absorb the tooth-on-tooth impact and the starting impact and that will readily rotate off from a tooth-on-tooth impact, and in which a yielding guide-way is used to shift and drive the driven member.

With these and other objects in view which will become more apparent in the following description and disclosures in the drawing, this invention comprises the novel mechanism and combinations hereinafter described and more particularly pointed out and defined in the appended claims.

In the accompanying drawings, which illustrate a preferred embodiment of this invention, and in which similar reference numerals refer to similar features in the different views:

Figure 1 is an elevational view of a starter involving this invention with a portion of the engine fly wheel shown in elevation.

Figure 2 is an enlarged longitudinal sectional view through the starting mechanism.

Figures 3 and 4 are elevational views of a pair of telescopic driving members.

Figure 5 is an enlarged part-elevational and part-sectional view of the starter with the parts in driving position.

Figure 6 is a view similar to Fig. 5 of a slightly modified form of starter showing the parts in position when there is a tooth-on-tooth engagement, with the outer sleeve moved outwardly.

Figure 7 is an enlarged fragmentary sectional view of the driving members.

Figure 8 is an enlarged end elevational view of the starting mechanism.

Figure 9 is a diagrammatic view of the two driving members.

As shown on the drawings:

55 In referring to the drawings, there is shown

a motor 1 having a shaft 2 provided with a reduced section 3 upon its outer end. A hollow cylindrical sleeve 4 having a spiral slot 5 which begins with a straight transverse portion 5^a at its initial point, and a long extending bearing hub 4^a at its outer end is secured upon the reduced portion 3 of the motor shaft by means of the bolt 7. The cylindrical sleeve 4 has an interior diameter of such a size as to receive the driven member therein. This driven member is shown in the form of a pinion 6 having teeth at one end and a smooth hub at the other end from which a radial stud 8 projects into the spiral slot or guide-way 5. The ends of the slot 5 are substantially as wide as the diameter of the head of the stud 8; the intermediate portion of the slot 5 is however considerably wider than the diameter of the head of the stud 5 for a purpose that will appear later.

A second sleeve 9 slidably telescopes over the sleeve 4 and is provided with a short bearing hub 9^a which has a slidable fit upon the hub 4^a of the sleeve 4. The inner end of the sleeve 9 is in the form of a spiral cam surface 9^d which begins with a straight transverse portion 9^b and a concave notch 9^c which correspond in contour to the initial point or beginning of the slot 5. The sleeve 9 is provided with a slot 10 through which a stud or pin 11 rigidly secured in the sleeve 4 projects whereby the sleeve 9 may slide relatively to the sleeve 4 but is constrained to rotate therewith. In Figure 9 is shown the normal position of the two sleeves 4 and 9 and it will be noted that the spiral cam surface 9^d of the sleeve 9 normally overlaps a portion of the slot 5 in the sleeve 4. It will also be noted that the front face of the slot in the sleeve 4 is substantially a true spiral with the exception of the short transverse portion while the rear face is cut back so that stud 8 can recede therein when the sleeve 9 yields outwardly due to a tooth-on-tooth engagement of the pinion 6 and engine gear 14, and also when the sleeve 9 moves outwardly to compress the spring 17 for forming a yielding frictional driving connection.

A collar 12 is secured upon the end of the hub 4^a of the sleeve 4 by the bolt 7, and a comparatively weak coil spring 13 is positioned upon the hub 4^a with its ends abutting the collar 12 and the end of the hub 110

9^a of the collar 9. The function of this spring is to retain the sleeve 9 against the sleeve 4 and to provide a ready yield therefor when there is a tooth-on-tooth engagement of the pinion 6 and the gear 14 on the fly-wheel of the engine.

A cylindrical housing or barrel 15 is freely mounted upon the collar 5 and provided with an inwardly turned flange 15^a at its inner 10 end which slidably rests upon the hub 9^a of the sleeve 9. A split ring 16 is sprung into a suitable internal groove in the outer end of the housing 15 and normally rests against the collar 12 as shown in Figure 2 to 15 limit the inward movement of the housing.

A heavy or strong coil spring 17 is confined under a predetermined compression within the housing 15 with its ends abutting the collar 12 and the inwardly turned flange 15^a 20 of the housing 15. This spring normally projects the housing inwardly until the split ring 16 abuts the collar 12 as shown in Figure 2. In this position, the flange 15^a is spaced a short distance from the end of the 25 sleeve. However, upon sufficient outward sliding movement of the sleeve 9, it will abut the inwardly turned flange 15^a of said housing and slide the same outwardly as shown in Figure 5, thereby compressing the strong 30 coil spring 17 and forming a yielding driving connection for the pinion, as will later appear.

In the modification shown in Figure 6, all the parts are similar to those just described 35 with the exception that the inner sleeve 4^c corresponding to the sleeve 4 in the first form is provided with a slight shoulder 18 on the outer wall of the slot 5, which is slightly modified as shown in Fig. 6 so that 40 if the pinion 6 and gear 14 come into contact so as to produce a tooth-on-tooth engagement, the sleeve 9 will yield outwardly against the tension of the spring 13 uncovering said shoulder 18, and the stud 8 on the 45 pinion 6 will be operated against said shoulder which offers sufficient frictional resistance to allow the pinion to be rotated from its tooth-on-tooth engagement. In order to clearly illustrate the shoulder 18, the sleeve 50 9 has been shown in Fig. 6 as shifted outwardly beyond the stud 8. It should, however, be understood that in operation the cam surface 9^d is always spring-impelled 55 against the stud 8.

The operation of this starter will now be described. Figure 1 shows the parts in normal position with the stud 8 seated in the end of the slot 5 of the sleeve 4 and in the 60 part-circular recess 9^e of the sleeve 9. Upon starting the motor, the two slidably coupled sleeves 4 and 9 will jointly rotate. At first the stud 8 on the pinion 6 will not be moved out of the end of the slot on account of the short transverse portions of the slot 5 and 65 the transverse portion 9^b on the sleeve 9. It

will require one or more revolutions of the motor shaft before the stud 8 on the pinion is moved into engagement with the spiral part of the guideway, so that the motor will be able to acquire sufficient torque for starting a stiff engine. It will, of course, be understood that the inertia of the pinion 6, 70

which is loosely mounted upon the motor shaft, is sufficient to prevent or retard its rotation so that the sleeves 4 and 9 will rotate 75 relatively thereto. When such relative rotation has brought the radial stud 8 on the pinion into engagement with the spiral portion of the guideway, the pinion 6 will be moved longitudinally into engagement with

the engine gear 14. In referring to Figure 80 9, it will be seen that the spiral face 9^d of the sleeve 9 not only extends beyond the far wall of the slot 5, but the slope thereof is also greater than the slope of the front wall of

the slot 5 in the sleeve 4; in other words, the spiral face 9^d of the sleeve 9 converges toward the front or opposite wall of the slot 5 so that a yielding wedging action occurs 85 upon the stud 8 shortly after it emerges from the short transverse portion of the guideway. This initial yielding wedging action will normally be sufficient to rotate the pinion 6 off of a tooth-on-tooth engagement with the gear 14 when one occurs.

As the pinion 6 is longitudinally moved into 90 engagement with the gear 14, the stud 8 traveling in the converging guideway will expand the same through the slidable characteristic of the sleeve 9, and when the pinion 6 has been brought into full meshing relation with the engine gear 14, the stud 8 will be substantially in the position illustrated 95 in Figure 5, some distance from the end of the guideway, in which position the sleeve 9 will have been shifted longitudinally and moved the housing 15 for further compressing the strong spring 17, as shown in Figure 100 5. That is, as the stud 8 is forced into the converging or narrow end of the slot formed by the opposing walls of the sleeves 9 and 4, the sleeve 9 will be forced back against the tension of the spring 17 which is designed 105 to resist a predetermined load.

When the force acting against the spring 17 equals the force necessary to rotate the engine gear 14, the sleeves 9 and 4 and pinion 6 will rotate 110 conjointly and the engine will be started. The force of the spring 17 acts in a longitudinal direction. It is a compressible force 115 as distinguished from a rotational or torsional force, so that when the starter is cranking the engine, the pinion 6 will be yieldingly held by a longitudinally directed

yielding force. The tension of the spring 17 should, of course, be so designed as to resist the cranking load before the stud 8 reaches the end of the slot, so that if the engine should back kick, the spring 17 will be 120 further compressed, allowing the stud 8 to 125 130

move to the end of the slot, so there will be an initial yield upon a back kick of the engine when the same is under its highest compression.

5 When the engine has been cranked as above explained, the engine gear will overrun the pinion 6 and cause the same to automatically travel out of mesh, as is obvious.

The spring 13, which abuts the end of the 10 sleeve 9, is adapted to be compressed before the spring 17, as can be readily seen by referring to Figure 2. This spring 13 is adapted to yield when there is a tooth-on-tooth engagement of the gears 6 and 14, and 15 when such an action occurs, the sleeve 9 will slide longitudinally against the tension of the spring 13, allowing the stud 8 to move therewith on account of the wide intermediate portion of the slot 5. If the resistance 20 of the light spring 13 is overcome, the heavy spring 17 may come into play, so the frictional resistance of the cam surface 9^d against the stud 8 will be ordinarily sufficient to rotate the pinion off of its tooth-on-tooth engagement. Such action, however, 25 will be expedited in using an inner sleeve with an inclined shoulder or abutment 18, as illustrated in Figure 6.

The spiral face 9^d of the sleeve 9 and the 30 opposite wall of the slot 5 form, in effect, a yielding and expansible guideway which will expand when the stud 8 comes into wedging contact with the walls of such guideway; and such expansion of the guideway will 35 continue until the expanding force overcomes or equals the torque necessary to start the engine.

It will accordingly be apparent that the 40 gears 6 and 14 will go into mesh under a yield and the engine will be started under a yielding force. Consequently there will be little or no shock or clashing of the gears during the starting operation, and consequently there will occur no appreciable cutting or damaging of the gears.

I am aware that numerous details of construction may be varied through a wide range without departing from the principles of this invention, and I therefore do not purpose limiting the patent granted hereon otherwise than necessitated by the prior art.

I claim as my invention—

1. In an engine starter comprising a motor having an extended shaft, a sleeve secured upon said shaft, said sleeve having a cylindrical portion spaced from the shaft and provided with a spiral guideway, a pinion secured upon said shaft within said sleeve and having a radial stud projecting into said guideway, a second sleeve surrounding said first sleeve and longitudinally slidable with respect thereto, and coupled therewith for conjoint rotation, said second sleeve having a spiral face overlapping a portion of the 55 spiral slot of the first sleeve, and a yielding

spring confined under a predetermined compression positioned around said shaft adjacent the end of said second sleeve.

2. In an engine starter comprising a shaft, a cylindrical sleeve secured upon said shaft and having a spiral guideway, a second sleeve slidably coupled to said first sleeve and having a spiral face in opposed relation to a wall of said spiral guideway, and yielding means adapted for compression by the 70 sliding movements of said second sleeve, and a driven member having a stud projecting into said guideway.

3. In an engine starter comprising a shaft, a pair of relatively slidable members coupled together for conjoint rotation secured to said shaft, said members having opposed spiral walls, and a pinion having a radial 75 stud projecting between said walls.

4. In an engine starter comprising a shaft, a pair of relatively movable members mounted upon said shaft, said members having opposed spiral walls, a driven member having a stud projecting between said walls and yielding means for limiting the relative 80 movement of said members.

5. In an engine starter comprising a shaft, a pair of relatively movable telescopic members supported upon said shaft, said members having opposed spiral walls, a driven member on said shaft and having a stud projecting between said walls and yielding means for limiting the relative movements of 85 said members.

6. In an engine starter comprising a shaft, a driven member mounted thereon and having a radial stud and means for longitudinally moving said member and coupling the same for rotation with said shaft comprising a pair of relatively yieldable members defining a spiral and yieldable guide-way for receiving said stud and means for limiting the relatively yielding movements of 90 said members.

7. In an engine starter comprising a shaft, a driven member loosely mounted upon said shaft and having a radial stud, a pair of relatively movable members defining a spiral guide-way therebetween for receiving said stud and means under compression for 95 limiting the relative movement of said members.

8. In an engine starter comprising a shaft, a driven member mounted upon said shaft and having a radial stud, a pair of relatively 100 movable members having opposed spiral walls of different pitch for defining a guideway with converging walls for receiving said stud, and means for yieldingly limiting the relative movement of said members.

9. In an engine starter comprising a shaft, a pinion loosely mounted upon said shaft, a pair of relatively movable members having opposed spiral walls for controlling said 105 pinion, said pinion having a stud project-

ing between said spiral walls and means for yieldingly controlling the relative movements of said members.

10. In an engine starter comprising a shaft, a driven member loosely mounted upon said shaft, a pair of relatively movable concentric members defining a yielding guide-way therebetween for coaction with said driven member, said driven member having a stud projecting into said guideway.

11. In an engine starter comprising a shaft, a pinion loosely mounted upon said shaft and having a radial stud projecting therefrom, a pair of relatively shiftable concentric members mounted upon said shaft, one of said members having a guide-way for receiving said stud and the other having a spiral face engaging said stud and yielding means adapted for compression by said second member for the purpose described.

12. The combination with an engine member of a starter therefore comprising a shaft, a driven member loosely mounted upon said shaft and having a radial stud, a pair of relatively slidable concentric members mounted upon said shaft, one of said members having a spiral guide-way for receiving said stud, one wall of said guide-way having a shoulder and the other member having a spiral face normally overlapping said shoulder but adapted to be shifted longitudinally when there is an abutting relation of said engine and driven member for bringing said stud in contact with said shoulder for the purpose described.

13. The combination with an engine member, of a starter therefore comprising a driven member adapted to be brought into coacting relation with said engine member and means for controlling said driven member comprising a pair of relatively movable members having coacting parts for longitudinally shifting and rotating said driven member, said driven member having a stud projecting between said relatively movable members, and yielding means for controlling the coacting relation of said members.

14. The combination with an engine member, of a starter therefore comprising a driven member adapted to be brought into coacting relation with said engine member, and means for controlling said driven member when it has an abutting relation with said engine member comprising a pair of relatively shiftable members and means on one of said members adapted for engagement by said driven member when the other member has been shifted, for rotating said driven member from its abutting relation.

15. In a starter comprising a shaft, a pinion loosely mounted upon said shaft and having a radial stud, a pair of relatively shiftable concentric members having over-

lapping spiral walls for engagement with said stud, yielding means engaging the member with the overlapping wall, and adapted to yield to bring said stud into engagement with the overlapped wall, said overlapped wall having a shoulder for engagement with said stud for the purpose described.

16. In an engine starter comprising a shaft, a pinion loosely mounted upon said shaft and having a radial stud and a pair of yieldingly maintained members defining a spiral expansible guide-way therebetween for receiving said stud.

17. In an engine starter comprising a shaft, a pinion loosely mounted upon said shaft and having a radial stud, a pair of relatively movable concentric members having opposed spiral walls for forming a guide-way for receiving said stud and a spring confined under compression adapted to limit the relative movement of said members.

18. The combination with an engine member, of a starter therefore comprising a driven member, driving mechanism therefore comprising relatively movable members said driven member having a stud extending between said movable members, and means on one of said members for engagement of said driven member when the latter is in abutting relation with said engine member.

19. The combination with a gear on an engine shaft, of a starter therefore comprising a pinion, driving mechanism adapted for longitudinally moving and rotating said pinion comprising a pair of relatively movable members, said pinion having a stud extending between said members and means on one of said members for engagement by said driven member when the latter is in a tooth-on-tooth relation with the gear on the engine shaft for the purpose set forth.

20. In an engine starter comprising a shaft, a pinion loosely mounted upon said shaft and having a radial stud projecting therefrom, a pair of relatively slidable members defining a converging guideway therebetween for receiving said stud, mounted upon said shaft, and a pair of coil springs of different tension bearing upon one of said members.

21. A starter for engines comprising a rotatable shaft, a pinion mounted on said shaft having a stud projecting therefrom, mechanism providing a guideway connected to said shaft for controlling the movement of said pinion, one wall of said guideway being in yielding frictional contact with said stud during the longitudinal movement of said pinion.

In testimony whereof I have hereunto subscribed my name.

ODILON BRISBOIS.
